Primary Examiner—Dominic Simone

(74) Attorney, Agent, or Firm—Banner & Witcoff, Ltd.

(57) CLAIM

The ornamental design for a portion of a shoe upper, as shown and described.

DESCRIPTION

FIG. 1 is a perspective view of a portion of a shoe upper showing my new design;

FIG. 2 is a side view thereof;

FIG. 3 a front view thereof;

FIG. 4 is a rear view thereof; and,

FIG. 5 is a top view thereof.

The broken line showing of the circular eyelet, the boundary of the claimed region and the remainder of the shoe is for illustrative purposes only and forms no part of the claimed design.

1 Claim, 2 Drawing Sheets
